MACHINE FOR ASSEMBLING CUSHION SPRING UNITS

Thomas J. King, Oak Park, and Fred R. Zimmerman, Chicago, Ill., assignors to The Gerrard Company, Inc., Chicago, Ill., a corporation of Delaware

Application January 4, 1934, Serial No. 705,266

9 Claims. (Cl. 140—3)

This invention resides in the provision of a novel machine for automatically binding together coil springs to form cushion units.

One object of the invention is to provide a machine in which the springs are bound together top and bottom in rows by means of a plurality of continuous wires which connect each row with the following row while at the same time allowing for a certain amount of separative movement between adjacent rows.

Another object is to provide a machine of the character described which is fully automatic in its operation and which will turn out the completed cushion units at a high rate of speed.

Other more specific objects and advantages will be apparent to those skilled in the art upon a full understanding of the construction, arrangement and operation of the machine.

One embodiment of the invention is presented herein for the purpose of exemplification, but it will of course be appreciated that the invention is susceptible of being incorporated in other structurally modified forms coming equally within the scope of the appended claims.

In the accompanying drawings:

Fig. 1 is a side view of the machine;

Fig. 2 is an end view of the machine, with certain portions broken away;

Fig. 3 is a side view of the lower forming head in the machine;

Fig. 4 is a plan view of a portion of the lower head;

Fig. 5 is an end view of the spring straightening device, taken on approximately the line 5—5 of Fig. 3;

Fig. 6 is an end view of the wire twisting device, taken on approximately the line 6—6 of Fig. 3;

Fig. 7 is a side view of the main clutch;

Fig. 8 is a partially sectioned end view of the clutch, taken on the line 8—8 of Fig. 7; and

Fig. 9 is a section through one of the wire guideways, taken on the line 9—9 of Fig. 4.

The machine which forms the subject matter of this invention is adapted to bind together coil springs by utilizing the particular twisted wire tie formation shown in Zimmerman Patent No. 1,847,230, but it will of course be appreciated that with minor modifications the machine can be used to produce other kinds of connections between the springs.

The various mechanisms which constitute the machine are enclosed within an open rectangular frame 10 which is composed of side members 11 and end members 12. The machine is provided

with a flat horizontal passageway 13 which extends through the frame from one end to the other. This passageway is approximately equal in height to the springs 14 which are adapted to be bound together by the machine and it is practically as wide as the frame. The springs are fed into one end of the passageway, in transversely extending rows, and advance through the same with a step-by-step movement, emerging from the other end of the passageway with the springs in each row tied to each other top and bottom, with a plurality of wires and with each row connected to the preceding and following rows with the same wires, all as shown in Fig. 4 and as described in detail in the above mentioned Zimmerman patent.

The bottom of the passageway 13 is defined by a plurality of longitudinally extending strips 15 which are mounted at their ends on tie rods 16 carried by the side members 11 of the frame. The strips 15, which are positioned on edge, are arranged in pairs, with the strips in each pair spaced apart approximately the diameter of the springs 14, and with the adjacent strips of adjoining pairs in lateral abutment with each other. The upper edges of the strips 15 form supporting guides for the upper stretches of a plurality of specially constructed chains 17 which together form an endless bed conveyor 18. At the out-feed end of the passageway the chains 17 are trained over sprocket wheels 19 which are secured to a shaft 20, while at the in-feed end the chains are trained over a curved sheet metal shield 21. The shaft 20, through which the chains of the conveyor are driven, is journaled in bearings in the upper ends of two arms 22, which arms are pivotally attached at their lower ends to the side members 11 of the frame by studs 23 and are secured in any desired position by locking bolts 24. The bolts 24 pass through arcuate slots 25 in the side members 11, and the ends of the shaft 20 likewise pass through arcuate slots 26 in the side members. The curved shield 21 over which the chains are trained at the in-feed end of the machine is secured at its ends to the side members 11 by bolts 27, which bolts are positioned in horizontally elongated slots 28 in the side members. By loosening the bolts 24 and 27, various adjustments can be made with respect to both the position and the tautness of the conveyor 18.

Each of the chains 17 of the lower conveyor 18 consists of a series of plates 29 (see Figs. 3 and 4) which are provided with circular seats 30 for the centered reception of the lower ends 31

of the springs 14, and each of the plates 29 is pivotally connected to the preceding and following plates by pairs of links 31 which project at their ends over the edges of the seats 30 and 5 lock the ends of the springs in the seats when the plates and links are moved into the same plane at the upper edge of the shield 21.

The upper stretch of the conveyor 18 is advanced intermittently by means of a dog 32 which 10 engages with the teeth of a ratchet wheel 33 on one end of the shaft 20. The dog 32 is pivotally mounted on an arm 34 which swings about the shaft 20 and is pressed resiliently against the teeth by any suitable means. The lower end of 15 the arm 34 is pivotally connected to one end of a rod 35, and the other end of the rod 35 is pivotally connected to the upper end of an arm 36. The arm 36 is pivoted at its lower end to the frame of the machine and is provided intermediate its ends with a cam-following roller 37 which is maintained in engagement with the periphery of a cam 38. When the roller 37 rides into the relieved portion of the cam, under the influence of a tensioned spring 39 which is attached to the rod 35, the dog 32 will move back 20 into a position behind one of the teeth of the ratchet wheel 33, and when the roller rides onto the high portion of the cam the dog will turn the ratchet wheel through an angle corresponding to 25 one of the teeth, thereby advancing all of the chains of the conveyor simultaneously a distance equal to the spacing of the seats for the springs. The cam 38 is mounted on one end of a shaft 40, which shaft is intermittently rotated, one revolution at a time, from a main drive shaft 41 by 30 the power transmitting mechanism hereinafter described.

The shaft 41, which is provided at its outer end with a belt pulley 42, carries a pinion 43 which 40 meshes with a gear 44 on a stub shaft 45. The shaft 45 carries a pinion 46 which meshes with a gear 47. The gear 47 (see Fig. 8) is journaled on a shaft 48 and is adapted to intermittently rotate the shaft 48, one revolution at a time, 45 when a spring-pressed clutch pin 49 is permitted to move into a recess 50 in the gear. The pin 49, which is mounted in a carrier 51 secured to the shaft 48, is adapted to be withdrawn from clutched engagement with the gear 47 by a beveled finger 52 on a downwardly spring-pressed arm 53 (see Fig. 7). The arm 53 is pivotally mounted at its lower end on a shaft 54 and bears at its upper end against the periphery of a cam 55 on the previously described shaft 40. After 50 the cam 55 has made one complete revolution, a relieved portion 56 in the cam will permit the arm 53 to swing downwardly under the action of a spring 57, whereupon the beveled end of the finger 52 will engage with an annular shoulder 55 on the pin 49, causing the latter to be withdrawn from engagement with the gear 47. As soon as the gear 47 has been disengaged, the shaft 48 will come to rest. The shaft 40 is rotated by a gear 59 on the shaft 48 which meshes 60 with a gear 60 on the shaft 40. Rotation of the shafts 40 and 48 is started by depressing a foot lever 61, which lever is pivotally mounted on a cross rod 62 and is connected to the arm 53 by a link 63. When the foot lever 61 is depressed, the beveled end of the finger 52 will be withdrawn 65 from its engagement with the pin 49, allowing the constantly rotating gear 47 to be clutched to the shaft 48. In other words, when the foot lever 61 is operated, the shafts 40 and 48 will 70 each make one complete revolution before com-

ing to rest and the resulting movement of the cam 38 on the end of the shaft 40 will cause the lower conveyor 18 to be advanced one step.

The shafts 40 and 48 control the operations of all the mechanisms which cooperate to bind together the lower ends of the springs 14 resting on the lower conveyor 18. They also indirectly control the operation of all the mechanisms which cooperate to bind together the upper ends of the springs, but as the upper set of mechanisms is in 10 large measure a duplication of the lower set the latter will first be described.

The lower set of mechanisms includes—in addition to the already described intermittently advancing conveyor 18—means for feeding the 15 wires used in connecting the springs; means for taking the lower circular ends of the springs in each row and shaping the adjacent portions thereof into straight contiguously disposed sections; means for placing resiliently yieldable wave-like formations in each wire intermediate the 20 portions used in tying the springs together; means for forming a loop in each wire between each two wave-like formations; and means for twisting such loops about the straight abutting 25 sections of the springs.

The wires 64 which are used in binding together the lower ends of the springs are carried in coiled form on reels 65 (see Fig. 1) and pass from the reels over grooved feed rolls 66 into 30 tubular guides 67. The guides 67, which are located at the in-feed end of the machine, curve upwardly and discharge the wires in the direction of feed of the conveyor 18 in the passageways present between the strips 15 on which the 35 chains of the conveyor are supported. From the guides 67 the wires pass between periodically meshing parallel pins 68 which are carried by disks 69 (see Figs. 3 and 4). The disks are arranged in pairs in the passageways, with the disks in each 40 pair in slightly spaced but marginally lapped relation, whereby to provide an opening between the same for the wire. The disks in each pair are secured to the upper ends of short upright shafts 70 which are caused to rotate at the same 45 speed but in opposite directions by intermeshed pinions 71 on the shafts. One of the shafts in each pair is provided at its lower end with a spiral gear 72 which meshes with and is driven by a spiral gear 73. All of the spiral driving 50 gears 73 are secured to a shaft 74 which is journaled crosswise in the frame just below the strips 15. The shaft 74 is driven from a countershaft 75 by a chain 76 which is trained over sprockets on both shafts, while the countershaft 75 is in 55 turn driven from the previously described control shaft 40 by a chain 77 which is likewise trained over sprockets on those shafts.

The pins 68 are eccentrically grouped with respect to the axes of the disks 69, with the result 60 that they act only on relatively short sections of the wires and leave the relatively long intervening sections straight, the latter sections passing freely through the openings present between the overlapped portions of the disks notwithstanding the 65 movement of the pins on the latter. The pins 68 are so spaced in their closest positions of approach as to bend the wires back and forth without gripping or clamping the same. The wave-like formations produced by the pins are shown at 78 in 70 Fig. 4.

Should any of the wires 64 offer too much resistance to forward movement in their passage through the zone of the deforming pins 68, that particular wire will of course become taut near 75

the lower end of the guide 61 it is entering, where normally a certain amount of curved slack is present in the wire. When this occurs, the wire will move upwardly in straightening out and will force an overlying finger 82 upwardly (see Fig. 1). The finger 82, which is connected to a toggle link 83, will act with a second toggle link 84 to swing an arm 85 downwardly. The arm 85, which is pivotally mounted at one end on the cross rod 62, is provided at its other end with an idling roll 86, which roll will clamp the wire firmly down against the previously described feed roll 66, thereby accelerating the speed of travel of that particular wire. The feed rolls 66 are all mounted on a cross shaft 87 which is driven from the control shaft 48 by a chain 88 which is trained over suitable sprockets on both shafts. It will of course be understood that each of the feed rolls 66 has associated with it one of the idling rolls 86, and 20 that there is a separate finger 82 for each of the idling rolls.

The devices which are employed to straighten out the adjacent sections of the lower circular ends of the springs 14 are located in the passageways between the strips 15 at points just in advance of the paired disks 69. Each of these devices consists of a flat rectangular plate 90 (see Figs. 3, 4 and 5) which is fastened at opposite sides to the strips and a pair of dies 91 which are adapted to move upwardly through an opening 92 in the plate and are also adapted when in their uppermost position to move toward each other between spaced projections 93 at opposite sides of the center of the opening 92. The opposed surfaces of the dies 91 and projections 93 which engage with the circular lower ends of the springs on the then stationary conveyor 18 are of such complementary shaping as to produce the straight subsequently bound sections shown at 94 in Fig. 4. 30 The dies 91 are mounted in a carrier 95 which is adapted to move up and down in a rectangular guideway 96 provided between strips 15, and the carrier 95 is in turn supported on a cross shaft 97. The dies are pivoted at 98 to the carrier and the 40 lower ends of the dies are equipped with rollers 99 which are adapted to engage with the opposite faces of a double cam disk 100 on the shaft. The upper working portions of the dies 91 are normally maintained separated, with the rollers 99 hugging the opposite faces of the cam disk 100, by the action of compressed springs 101. When the disk 100 turns with the shaft 97 into a position wherein the high portions of the cam surfaces cause the rollers to move laterally, the dies 50 91 will of course be brought together on the interposed portions of the springs 15 to produce the formations 94.

The shaft 97—which forms the support for all of the die carriers 95 and at the same time constitutes the operating means for all of the paired dies 91—is journaled in a movable frame 105 (see Fig. 3). The frame 105 includes two longitudinally extending side members 106 which are pivotally mounted on a cross shaft 107 near the 60 in-feed end of the machine. The other ends of the frame members 106 are provided with rollers 108 which rest on cams 109. The cams 109 are secured to the previously described control shaft 48 at points adjacent the sides of the main frame 70 of the machine. When the rollers 108 ride down into the low portions of the cams 109, the moving frame 105 will lower, bringing the dies 91 below the level of the conveyor 18, and when the rollers ride onto the high portions of the cams the mov-

ing frame will rise, bringing the dies 91 into their operative positions.

The shaft 97 is rotated at proper intervals by a sprocket 110 on one end of the same (see Fig. 1) which engages with the outer side of a chain 111 which is trained over a sprocket 112 on the shaft 107 and over another sprocket 113 on another cross shaft 114, which cross shaft is carried by the moving frame 105. The shaft 107 is in turn driven from the previously described control shaft 48 by a chain 115 which is trained over sprockets on both shafts. As rotation of the shafts 97, 107 and 114 is not intended to take place during the first part of the period of rotation of the control shaft 48, due to the fact that during such time the moving frame 105 is being raised, a spring-pressed pin clutch 116 (see Fig. 3), on the order of the previously described clutch 49, is provided on the shaft 107 for disconnecting the chain drive 115 from that shaft. The clutch 20 116 is released by a pivoted wedge finger 117 which is connected to a latch finger 118 by a link 119. The lower free end of the finger 118 projects into the path of a stud 120 on one side of the previously mentioned cam 109, with the result 25 that when the stud 120 moves the finger 118 the clutch 116 will be operated, causing the shaft 107 to turn until the clutch 116 is automatically thrown out by the finger 117.

The loops in the wires 64, from which the twists 30 are subsequently made about the straightened portions of the lower ends of the springs, are produced in the wires by means of upwardly projecting die members 125 (see Figs. 3 and 4). All of the die members 125 are pivotally mounted at 35 their lower ends on a cross rod 126 carried by the frame 105, which form of mounting allows the die members to travel practically straight up and down in guideways provided for the same between the strips 15 notwithstanding the slightly 40 arcuate movement of the frame 105. As each of the die members 125 moves upwardly it engages with the under surface of one of the wires, and as it continues upwardly it bends the overlying portion of the wire into an inverted U-shaped 45 loop, the wire meanwhile being held down against the side surfaces of the die by studs 127 and 128. Each wire, in moving into the path of one of the die members 125, passes through a guiding conduit 129 where it is engaged by a pair of resiliently 50 contracted directing fingers 130.

As each of the dies 125 moves upwardly to form the loop in the wire, the associated stud 127, which is slidably mounted in a guide block 131, is projected laterally into its operative position 55 above the wire by a pivoted bell crank lever 132 (see Fig. 9), which lever is actuated by a rod 133. The rod 133 extends down into a socket member 134 which is carried by the moving frame 105, and as a result of this connection the stud 127 is projected when the frame 105 is raised and is retracted when the frame is lowered. This retraction of the stud 127 is necessary in order to permit the upstanding loop in the wire to travel past that point into a guideway 135 of inverted T- 65 shaped section located at the far side of the die. A spring 136 is preferably introduced between the rod 133 and the socket 134 in order to effect a spring-pressed projection of the stud 137 at the beginning of the upward movement of the frame 70 105, the spring 136 yielding as the frame continues its upward movement with the stud in operative position. The other forming stud 128 associated with each of the dies 125 is brought down on the upper surface of the wire by the oscilla- 75

tory movement of a bell crank lever 137 on which it is mounted. The other arm of the lever 137 carries a roller 138 which is engaged and forced upwardly by an adjustably positioned block 139 on the top of the frame 105.

From the loop forming dies 125 the wires 64 travel upwardly at an inclination through the guideways 135 into the plane of the conveyor 18, where they assume upright positions alongside the horizontally disposed straight sections of the lower ends of the springs 14.

The devices which act to twist the upstanding loops in the wires about the parallel portions of the lower ends of the springs, are positioned in the passageways between the strips 15 at points beyond the ends of the guideways 135. Each of these devices consists of a wire twisting unit 141 (see Fig. 6) which is movable vertically in a guideway 142 and is mounted on a bearing 143 which is journaled in an upright position on the previously described shaft 114. Each unit contains a radially slotted wire twisting pinion 144 and two pairs of wire holding jaws 146 which are pivotally mounted at opposite sides of the carrier in alignment with the slot 147 in the pinion.

As soon as the wires 64, with the upstanding loop formed therein, come to rest above the twisting unit, the latter will move upwardly through the guideway 142 and the looped portion of the wire, together with the contiguously lying straight portion of the lower ends of two of the springs, will be received in the slot 147 of the pinion. As the unit reaches its fully elevated position, the jaws 146 will close on the wire at opposite sides of the looped portion and two other pairs of jaws 148 will close against the jaws 146 on the adjacent circular portions of the lower ends of the springs, thereby holding all of the wire parts, with the exception of the looped portion, against movement. Rotation of the pinion 144 will thereupon twist the looped portion of the wire one, two or three times around the two straightened portions of the springs, as desired, producing a secure hinge-like connection between the springs.

The slotted wire twisting pinion 144 meshes with a pinion 149 which is located below the same on a stub shaft 150, and the shaft 150 is driven from a cross shaft 151 by intermeshed spiral gears 152 (see Fig. 3) on those shafts. The shaft 151, which serves as the driving means for the twisting pinions of all of the units, is provided at one end with a pinion 153 (see Fig. 1) which meshes with a gear 154 on the previously described shaft 114.

The jaws 148 are mounted on the upper ends of a pair of levers 155 which are pivotally mounted on the carrier 145 at 156. The upper ends of the levers 155 are normally maintained in separated relation to each other by a tensioned spring 157 which connects the lower ends of the levers, but when the carrier 145 approaches its uppermost position the lower ends of the levers 155 are spread apart by toggle links 158 which are connected to a plate 159 on a rock shaft 160. As the carrier reaches its uppermost position, the plate 159 is rocked to operate the toggle links 158 by an arm 161 which is secured to one end of the shaft 160. The arm 161 is oscillated downwardly by a roller 162 on the upper end of the same which moves into engagement with the lower edge of one of the strips 15. The jaws 148 are caused to move toward each other by the straightening of the toggle links 158 and the ac-

tion of the jaws 148 against the jaws 146 cause the latter also to move together, thereby clamping all of the wire parts in proper position for the twisting operation. The jaws 146 are normally maintained in their upper position by small springs 163 which are positioned between the jaws 146 and the jaws 148.

Through the operation of the above described mechanisms it will be understood that all of the coil springs 14 in each transversely extending row 10 are tied together at their lower ends by the wires 64 and that each row is connected to the row in advance of the same by means of the same wires, producing at the lower ends of the springs a fabricated cushion formation of the character disclosed in the previously mentioned Zimmerman patent. The upper ends of the springs are at the same time tied together in a similar manner by wires 64', through the instrumentality of another set of mechanisms which in all essential respects is substantially identical with those already described.

In this connection it will be observed in Figs. 1 and 2 that the upper ends of the springs 14 before being tied together by the wires 64' are mounted in seats on an upper chain conveyor 18', which conveyor is caused to advance intermittently in synchronism with the lower conveyor by means of a dog 32' which operates on a ratchet wheel 33' on the drive shaft 20' of the upper conveyor 30 and which is oscillated by a link 166 which connects with the corresponding ratchet mechanism of the lower conveyor. The wires 64' are fed from coils which are mounted on upper reels 65', the feeding mechanism consisting of positively driven feed rolls 66' and cooperating idler rolls 68', which idler rolls are controlled in their operation by wire engaging fingers 82'. Mechanisms for producing the wave-like formations in the wires, for straightening out and bringing together portions of the upper ends of the springs, for forming the upstanding loops in the wires, and for twisting such loops about the straightened portions of the ends of the springs, are all substantially duplicated in the upper part of the machine, with the mechanisms which require movement toward and away from the passageway 13 through the machine mounted on an upper moving frame 105'. The frame 105' is raised and lowered by means of a grooved cam 38' which corresponds in function to the cam 38, and the operating shafts 97', 107' and 114' are rotated by a chain 111', with the shaft 107' driven from the shaft 107 by a chain 167. The upper control shaft 40' on which the cam 38' is mounted is driven from the shaft 40 by a chain 168, while the shaft 87' on which the feed rolls 66' are mounted is driven from the control shaft 40' by a chain 169. The shaft 74' which rotates the disks which carry the wave-forming pins is driven from the shaft 74 by a chain 170. In this way all of the mechanisms which act upon the upper ends of the springs and the wires used to connect the same, are synchronized in their upper portions with the lower mechanisms, with the result that when the springs 14 emerge from the out-feed end of the machine they are permanently bound together, top and bottom, into a finished cushion unit.

The springs 14 may be positioned on the conveyors 18, 18' at the in-feed end of the machine, one at a time by hand, or they may first be assembled in rows in loading magazines of some kind and stripped from the magazines directly 75

into the seats on the conveyors, which latter method will of course permit of an increase in the speed of operation of the machine.

The upper section of the machine may be readily removed from the lower section to render the same readily accessible for adjustment or repair by merely disconnecting the previously described chain and link connections between the upper and lower heads and removing bolts 111 which connect 10 the side frames of the upper and lower heads together.

It will of course be appreciated that the particular means disclosed for shaping the ends of the springs, producing the wave formations in the 15 wires, bending the wires into loops, and twisting the loops about the springs, are so disclosed primarily for the purpose of exemplification, and are not to be considered as limitations on either the spirit or scope of the invention, since it will 20 be obvious that other instrumentalities might be employed for the same general purposes, and that some might be omitted while others of a generally similar character might be added. It will also be evident that changes in the character of 25 the cushion unit to be produced would of course require appropriate modifications in the nature, order and coaction of the mechanisms employed, the present invention residing in its broader aspects in the combination and coaction of mechanisms which together constitute the automatic 30 machine for the purpose of producing cushion units from individual coil springs.

It will also be apparent that different variations may be made in the matter of procedure 35 or results obtained. Thus, one side of the cushion unit might be assembled by connecting together the springs at the lower ends only thereof, this by omitting the top portion of the machine and using only the lower portion. The unit would then 40 of course be reversed on the machine and the other side assembled in a similar manner. Or the crimping arrangement for providing the convolutions in the connecting wires between the coils might be omitted adjacent the sides of 45 the machine in order to permit the outer or side wires to provide a stiffening effect for a border, and in this connection it might be desirable to employ a heavier gauge wire for the border. Or partially pre-formed wires might be used for the 50 connecting wires instead of forming these wires in the machine itself. In fact, it will be evident that the machine is susceptible of a number of such rearrangements, alterations and substitutions.

55 The designation "cushion unit" as used herein is of course to be understood as meaning any type of unit designed to give a cushioning effect. The units produced by the automatic machine 60 of the invention may be in the form of bed springs or bed mattresses, or they may be in the form of seat foundations such as are used in upholstered furniture and in the seats of automobiles, trains and the like. In fact, the units may be made up in various sizes and shapes to fit all now known cushion requirements.

We claim:

1. In a machine for automatically binding together coil springs to form cushion units, means for binding together a number of springs in a row with a number of wires which are disposed between adjacent springs, said means including rotary devices for twisting looped portions of the wires about adjoining portions of the springs, 70 and means for advancing the bound row, where- by to bind another row of springs by said first mentioned means with the same wires upon the next operation of the binding means.
2. In a machine for automatically binding together coil springs to form cushion units, means for binding together a number of springs in a row with a number of wires which are disposed between adjacent springs in generally right angular relation to the row, and means for advancing the bound row, said means including rotary devices for twisting looped portions of the wires about adjoining portions of the springs, whereby to bind another row of springs by said first mentioned means with the same wires upon the next 10 operation of the binding means.
3. In a machine for automatically binding together coil springs to form cushion units, means for simultaneously binding together a number of springs in a row with a number of wires which are disposed between adjacent springs in generally right angular relation to the row, and means for advancing the bound row, whereby to bind another row of springs by said first mentioned means with the same wires upon the next 15 operation of the binding means.
4. In a machine for automatically binding together coil springs to form cushion units, means for simultaneously binding together a number of springs in a row with a number of wires which are disposed between adjacent springs in generally right angular relation to the row, means for advancing the bound row, whereby to bind another row of springs by said first mentioned 20 means with the same wires upon the next operation of the binding means, and means for producing resiliently yieldable formations in the portions of the wires which connect the rows.
5. In a machine for automatically binding together coil springs to form cushion units, means for feeding coil springs through the machine in transversely extending rows, means for feeding wires through the machine in the same direction between the springs in each row, and means for twisting portions of the wires about abutting portions of the springs in each row.
6. In a machine for automatically binding together coil springs to form cushion units, means for feeding coil springs through the machine in transversely extending rows, means for feeding wires through the machine in the same direction between the springs in each row, means for forming a loop in each wire in registration with the springs in each row, and means for twisting the loops in the wires about abutting portions of the springs in each row.
7. In a machine for automatically binding together coil springs to form cushion units, means for feeding coil springs through the machine in transversely extending rows, means for feeding wires through the machine in the same direction between the springs in each row, means for placing a wave-like formation in each wire at intervals longitudinally thereof, means for forming a loop in each wire between each two wave-like 65 formations, and means for twisting transversely aligned loops in the wires about adjacent portions of the springs in each row.
8. In a machine for automatically binding together coil springs to form cushion units, means for feeding coil springs through the machine in transversely extending rows, means for feeding wires through the machine in the same direction between the springs in each row, means for straightening out portions of the correspondin- 70

end portions of the springs to bring such portions into parallel abutting relation, means for forming a loop in each wire in registration with the straightened portions of the springs, and means for twisting transversely aligned loops in the wires about the straightened portions of the springs in each row.

9. In a machine for automatically binding together coil springs to form cushion units, endless upper and lower conveyors arranged in spaced parallel relation and provided with means for temporarily holding the opposite ends of coil

springs in transverse rows, means for intermittently advancing the conveyors a distance corresponding to the distance between adjacent rows, means for feeding wires lengthwise of the conveyors between the corresponding ends of the springs in each row, and means for twisting the wires about adjacent portions of the springs, whereby to bind all of the springs in each row together and also bind each row to the preceding row.
